OVERHEAD TRAVELING CRANE

Henry A. Gorjanc, Wickliffe, Ohio, assignor to The Cleveland Crane & Engineering Company, Wickliffe, Ohio, a corporation of Ohio

Filed Dec. 16, 1960, Ser. No. 76,338

2 Claims. (Cl. 188—152)

The present invention relates to overhead traveling cranes and to industrial-type hydraulic brakes manually operable remotely from the brake proper.

The invention contemplates the provision of a new and novel overhead traveling crane having a hydraulically applied brake on the bridge controlled by an operator in a control cab suspended from the bridge and including means for automatically compensating for wear, etc., and wherein the sole hydraulic operating connection between the control or actuating mechanism in the cab and the brake proper is a single conduit.

The invention also contemplates a provision of a new and novel industrial-type hydraulic brake having the control or operator actuated mechanism located remotely from the brake proper and connected to the brake by a single conduit, the brake being self-adjustable to compensate for wear, etc.

The invention resides in certain constructions and combinations and arrangements of parts and further advantages of the invention will be apparent to those skilled in the art to which it relates from the following description of the preferred embodiment described with reference to the accompanying drawings forming a part of this specification, in which similar reference characters designate corresponding parts, and in which:

FIG. 1 is a fragmentary side elevational view of a traveling crane embodying the present invention;

FIG. 2 is an enlarged side elevational view of the brake proper taken approximately on the line 2—2 of FIG. 1, with parts broken away to better show the construction;

FIGS. 3 and 4 are end elevational views of the mechanism shown in FIG. 2, looking from the left and right, respectively;

FIG. 5 is a sectional view approximately on line 5—5 of FIG. 2;

FIG. 6 is an enlarged sectional view approximately on the line 6—6 of FIG. 2; and

FIG. 7 is an enlarged fragmentary view of a portion of FIG. 1 showing the operator actuated mechanism located in the crane control cab.

While the invention is susceptible of various modifications and alternate constructions, the preferred embodiment is shown in the drawings and herein described in detail. It is to be understood, however, that there is no intention to thereby limit the invention to the specific form disclosed, but it is the intention to cover all modifications and alternative constructions falling within the spirit and scope of the invention as expressed in the appended claims.

The traveling crane shown in the drawings comprises a bridge A upon which the usual trolley, not shown, carrying the hoist mechanism is adapted to travel transversely of the length of the crane runway comprising spaced rails 10, only one of which is shown, supported by suitable structure 11 which may be the side of the building within which the crane is located.

The crane further comprises end trucks at opposite ends of the bridge A, the wheels 12 of which ride upon the rails 10. Movement of the crane along the runway is effected by an electric motor B positioned on the bridge A and operably connected to one or more of the wheels 12 at each end of the bridge by gears 13 integral with the wheels 12 and in mesh with pinions 14 connected to the end of a shaft 15 extending the length of the bridge. The

2

shaft 15 is connected to the motor B by reduction gears, not shown, but located within a gear case 16. The electric motor B is adapted to be connected to and disconnected from the power lines in the usual manner by an operator manipulated controller 17 located in the cab C of the crane.

When it is desired to stop the crane at any particular location along the crane runway the power is disconnected from the motor B and a brake applied by the operator to the armature shaft of the motor. Alternatively the brake might be applied to the shaft 15 or directly to the wheels 12. Referring more particularly to FIGS. 2 to 5 of the drawings, the brake shown comprises a brake drum 20 fixedly secured to the end of the armature shaft 21 of the motor B opposite the end connected to the gear train therebetween and the shaft 15.

For the purpose of stopping the rotation of the brake drum 20 and/or holding it stationary, the drum is selectively engaged by two brake shoes 22, 23 provided with the usual brake lining 24, 25 and located at and engageable with radially opposite sides of the brake drum. The brake shoes 22, 23 are pivotally connected by pins 26, 27 to levers 30, 31, respectively, approximately mid-way between the ends of the levers. The lower ends of the levers are pivotally connected by pins 32, 33 to a built-up frame or base member 34 comprising angle irons 35, 36. The base 34 is detachably fixed to the bridge A of the crane. Friction devices 40, 41 are interposed between the brake shoes 22, 23 and the levers 30, 31 for holding the brake shoes in the proper relation to the respective arm by which they are carried so that they will not engage and drag upon the brake drum when the brake is not applied. Devices suitable for this purpose are well known in the art.

The levers 30, 31 project upwardly from the base 34 along opposite sides of the brake drum 20 and their upper ends are operatively connected to a fluid pressure motor D in such a manner that when fluid pressure is applied to the motor D the upper ends of the levers 30, 31 are moved towards one another and the brake applied. As shown, the upper end of lever 30, which is bifurcated, is connected by a pivot pin 42 to one end of a composite member 43, the opposite end of which is connected to the cylinder housing 44 of the fluid pressure actuated motor D. The member 43 comprises a member 45 pivoted to the upper end of the lever 30 and having one end of a tubular member 46 rectangular in cross-section welded thereto. The opposite end of the tubular member 46 is welded to a member 47 bolted to the housing 44 of the motor D.

The motor D is of the flexible diaphragm-type and the end of its piston rod 50 opposite to the end connected to the diaphragm is threaded into a suitably tapped hole in a member 51 slidably supported in the right-hand end of the tube 46, as viewed in FIG. 2 of the drawings. The member 51 is connected by a pin 52 to the upper bifurcated end of the lever 31. The pin 52 extends through elongated slots 55 in the opposite sides of the tube 46 so as to permit relative reciprocation of the member 51 within the tube 46. The member 51 is biased or continuously urged relative to the tube 46 towards the right, as viewed in FIG. 2, that is, in the direction to move the brake shoes 22, 23 clear of the brake drum 20, by a compression spring 57 housed within the tube 46 and interposed between the adjacent ends of the members 45, 51. The construction is such that the spring 57 biases the levers 30, 31 in directions away from the brake drum 20. The levers are moved in the opposite direction against the force of the spring 57 when the operator desires to apply the brake by pressure fluid admitted to the motor D in a manner hereinafter more specifically explained.

The lower end of the lever 30 includes a tubular member 60 fixed to the pin 32 rotatably supported in the angle members 35, 36 of the base 34 by self-lubricating

bushings. Opposite ends of the pin 32 project outwardly beyond the bushings where they are provided with drum-like members 63, 64 fixed to the right and left-hand ends, respectively, of the pin 32, as viewed in FIG. 5. The left-hand member 64 has an annular surface surrounded by a member 66 having a general shape of a split ring. The interior of the member 66 has suitable friction material fixed thereto, which material directly engages the annular surface on the member 64. The split ends of the member 66 have radially projecting lugs either welded or otherwise formed integral therewith, which lugs are continuously biased towards one another by a compression spring 72 interposed on the shank of a bolt 73 extending through one of the projecting ends of the member 66 and threaded into the other. The compression spring is interposed between the head of the bolt and the projecting end of the member 66 nearest thereto and continuously urges or biases the member 66 in a direction to frictionally engage the annular surface which it surrounds on the member 64. The fact that the bolt 73 is threaded into one of the projections on the member 66 provides an adjusting means for the spring 72. A lock or jamb nut may be used on the bolt, if such an expedient is considered necessary or desirable.

The member 64 has a pair of bosses 74, 75 formed integral therewith directly opposite the split therein and between which one end of a link 76 is pivoted by a pin 78. The opposite end of the link 76 is pivoted by a pin 80 to an arm 81 fixed to the projecting end of the pin 33 to which the lever 31 is fixedly connected. The ends 78, 80 of the link 76 are at opposite sides of the pins 32, 33, respectively, with the result that as either of the arms 30, 31 are moved towards or from the brake drum 20, the other arm moves a like distance unless one or the other of the brake shoes is in engagement with the brake drum 20. In this event the member 66 slips on the member 64 until both brake shoes are in engagement with the drum. When the brake shoes are subsequently moved away from the brake drum, each shoe will move in opposite directions at the same rate.

The member 63 on the near end of the pin 32, as viewed in FIG. 2 or on the right-hand end of the pin 32, as viewed in FIG. 5, has an annular surface similar to the surface of the member 64 and which surface is surrounded by a member 86 having the form of a split ring, the ends of which, adjacent the split, are provided with radial projections 90, 91 welded or otherwise formed integral therewith. The interior of the member 86 has suitable friction material fixed thereto in engagement with the annular surface of the member 33 surrounded thereby. The split ends of the member 86 are continuously urged or biased towards one another so as to maintain the member 86 in frictional engagement with the member 63 by a compression spring 93 positioned on the shank of a bolt 94 extending through the projection 90 and threaded into the projection 91 of the member 86. The spring 93 is interposed between the head of the bolt 94 and the projection 90. The threaded connection between the bolt 94 and the projection 91 provides means for adjusting the force of the spring 93. A lock nut may be employed on the lower end of the bolt 94, if desired.

The member 86 diametrically opposite the split therein is provided with an integral boss 95 to which an arm 96 is welded. The arm 96 extends generally lengthwise of the base 34 of the brake and the free end thereof is provided with an angle member 97 welded thereto and having a plunger-like member adjustably connected thereto in the form of a bolt 100 threaded through a suitably tapped aperture therein. A nut 101 threaded onto the end of the bolt 100 provides means for locking the bolt 100 in any position relative to the member 97 to which it may be adjusted. Movement of the lever 96 in a clockwise direction, as viewed in FIG. 2, is limited by an adjustable stop in the form of a bolt 102 threaded into an

annular member 103, the head of which bolt is adapted to engage the under side of the arm 96. The member 103 is welded to the outside of the angle member 35 adjacent to its right-hand end. The bolt 102 is provided with a nut 104 which serves to lock the bolt in adjusted position.

The head of the bolt 100 engages the upper end of the stem 105 of a poppet-type check valve, designated generally as 106. The stem 105 of the valve 106 is slidably supported in the valve housing 107 and the head of the valve is biased by a spring 110 upwardly into engagement with a valve seat formed on the underside of a partition 111 in the valve housing which divides the housing into inlet and outlet chambers 112, 113, respectively. The lower portion of the stem 105 of the valve 106 is provided with a plurality of flutes to allow the free passage of fluid between the inlet chamber 112 and the outlet chamber 113 when the valve is open.

The inlet and outlet chambers 112, 113 of the valve housing 107 are also connected by a ball-type check valve 115 located in a passage 116 in the partition 111 and biased by a spring 117 towards the left as viewed in FIG. 6. Fluid can pass through the check valve 115 only in the direction from the inlet chamber 112 to the outlet chamber 113. The inlet chamber 112 of the valve is connected by suitable conduit means 118 to a master cylinder mechanism E located in the control cab C of the crane and the outlet chamber 113 is connected by a flexible conduit means 118 to the fluid pressure motor D. The construction is such that when fluid pressure is applied to the conduit means 118 by the master cylinder mechanism E in excess of the pressure required to unseat either the poppet valve 106 of the check valve 115, fluid flows from the master cylinder through the conduit means 118, the inlet chamber 112, the apertures in the partition 111, the outlet chamber 113 and the conduit means 119 to the motor D, thus causing the motor D to move the brake shoes 22, 23 towards the brake drum 20 and the brake to be applied.

The ball-type check valve is preferably used as it can more easily be constructed to open at a relatively low pressure, two pounds and less, which is less than the pressure required to open the usual commercially available poppet-type valves. Obviously the ball-type check valve can be omitted if a suitable poppet-type valve is available. Having the check valve open at a relatively low pressure requires less pedal pressure at the master cylinder mechanism and gives a better "feel" on the break pedal and a smoother break operation than would otherwise be the case, because poppet-valves ordinarily require a relative high pressure to open.

Movement of the lever 30, which carries the brake shoe 22 towards the brake drum 20 causes the lever 96 to rotate in a clockwise direction, as viewed in FIG. 2, through the frictional connection between the members 63, 86. Movement of the lever 96 in a clockwise direction causes the head of the bolt 100 to either follow the end of the stem 105 of the poppet valve 106 or unseat the valve if it is not unseated and maintains the valve unseated even though there is a subsequent reversal of the flow of pressure fluid in the conduit means 118, until the arm 96 moves in a clockwise direction incident to the brake shoe 22 moving away from the brake drum 20.

Movement of the lever 96 in a clockwise direction is limited by the stop 102. The frictional connection, however, between the lever 96 and the drum-like member 63 on the pin 32 permits continued movement of the lever 30 and in turn the brake shoe 22 towards the brake drum if such movement is necessary because of the wearing of the brake lining 24 or for any other reason. It will be noted, however, that after each application of the brake the valve 106 will be permitted by the bolt 100 to close only after a predetermined movement of the lever 96 in a counter-clockwise direction. This will trap fluid pressure in the outlet chamber 113, the conduit means 118 and the motor

D. The amount of fluid trapped in these parts will always be such that the brake shoes will, subsequent to each application of the brake, return a predetermined distance from the brake drum 20 regardless of whether or not the brake linings wear. In other words, the brake is self-adjusted.

The master cylinder mechanism E shown comprises a diaphragm-type pressure fluid motor 120 of commercial construction bolted to the right-hand side of a plate 121 as viewed in FIG. 7 of the drawings. The plate 121 is a part of a built up frame structure comprising upright side members 123, 124 to which opposite ends of the plate 121 are bolted. The motor 121 has a cylindrical boss 125 formed integral therewith and through which the piston rod 126 of the motor projects and in which the piston rod is slidably supported. The boss 125 is provided with a threaded section upon which is mounted a nut 127 which secures the motor 120 to the plate 121. The piston rod 126 is spring-biased towards the left, as viewed in FIG. 7, and is adapted to be moved in the opposite direction by a roller 130 rotatably supported on a shaft fixed in a pair of downwardly extending projections formed integral with a member 132. The member 132 forms a part of a pedal, designated generally by the reference character 133, and which is rotatably supported by suitable bushings on a shaft 137 fixed in the side members 123, 124.

The pedal 133 comprises two plates 140, 141 welded together, the generally horizontal plate 140 of which is fastened by a plurality of set screws to the member 132. The opposite end of the pedal is provided with a foot rest 142 pivotally connected thereto. The member 132 is provided with a downwardly projecting plate 143 which engages the roller 130 when the pedal is depressed and a member 144 fixed to the side plates 123, 124 when the pedal is released. The pedal is biased in a clockwise direction as viewed in FIG. 7 by a spring 145 connected to the member 132 to the right-hand side of the shaft 137 and to housing of the master cylinder device. The engagement of the plate 143 with the member 144 limits rotation of the pedal in a clockwise direction under the action of the spring 145.

Secured to the top of the master cylinder housing or frame is a poppet-type check valve F comprising a valve proper in the form of a headed member 150, the head of which is biased by a spring 151 into engagement with a valve seat formed on the right-hand side of a partition in the valve housing 152. The stem of the valve 150 projects through and is slidably supported in the left-hand side of the housing 152 in a suitable manner. The valve is unseated or opened upon the operator releasing the pedal 133 by the engagement of the end of a bolt 153 adjustably connected to the plate 141 with the end of the stem of the valve 150.

The conduit 118 leading from the motor 120 of the master cylinder mechanism E to the brake proper has a T-fitting (not shown) therein, the stem of which is connected to the right-hand chamber of the check valve housing 152 as viewed in FIG. 7. The other or left-hand chamber or side of the check valve is connected by a conduit 160 to an oil reservoir 161 on the crane bridge located above the level of the brake proper. The construction is such that when the pedal is in its released position the conduit 118, etc., is connected to the reservoir 161 through the check valve F but upon initial movement of the pedal in the direction to create pressure in the motor 120, the conduit 115, etc., is shut off or isolated from the conduit 160 and the reservoir by the closing of the valve 150.

The preferred embodiment of the invention shown includes a third brake shoe 165 slidably supported in the frame 34 of the brake and biased towards the bottom of the brake drum 20 by a pluralit of compression springs

166. This brake is a so-called "parking brake" and is moved to released position by an electric solenoid 167, the circuit to which is under the control of the crane operator.

From the foregoing disclosure it will be apparent that 5 the objects heretofore enumerated and others have been accomplished and that there has been provided a novel overhead crane and braking mechanism. The braking mechanism proper is self-adjusting and connected to the master cylinder mechanism by one conduit only. This is 10 15 20 10 a decided advantage in many types of industrial equipment and particularly in cranes of the type herein disclosed.

While the invention has been described in considerable detail it is not limited to the construction shown and it is 15 the intention to cover hereby all adaptations, modifications and changes therein which come within the practice of those skilled in the art to which it relates.

Having thus described my invention, I claim:

1. In a braking apparatus, a frame or support, a brake drum, two generally parallel levers pivotally connected to said frame, at one radial side of said brake drum and extending to the opposite side thereof, brake shoes carried by said levers for engagement with said brake drum, a pressure fluid motor operatively connected with the ends of said levers opposite their pivots for moving said levers and in turn the brake shoes carried thereby towards said brake drum, means for moving said levers in a direction away from said brake drum, means for supplying pressure fluid to said pressure fluid actuated motor comprising conduit means connected to said motor, a check valve in said conduit means normally preventing the flow of pressure fluid from said motor, means including a member operatively connected to one of said levers adapted to move said check valve in the direction 30 35 40 45 50 55 60 65 to open the same upon movement of said lever towards said brake drum, a friction connection between said members and said lever, and a stop for limiting movement of said member incident to movement of said lever towards said brake drum.
2. In a braking apparatus, a frame or support, a brake drum, two generally parallel levers pivotally connected to said frame, at one radial side of said brake drum and extending to the opposite side thereof, brake shoes carried by said levers for engagement with said brake drum, a pressure fluid motor operatively connected with the ends of said levers opposite their pivots for moving said levers and in turn the brake shoes carried thereby towards said brake drum, means for moving said levers in a direction away from said brake drum, means for supplying pressure fluid to said pressure fluid actuated motor comprising a master cylinder located remote from said fluid pressure motor for supplying pressure fluid for operating said motor, a check valve located in the proximity of said pressure fluid motor normally preventing the flow of pressure fluid from said motor, conduit means connecting said motor and said check valve, a single hydraulic conduit between said master cylinder and said check valve means including a member controlling the closing of said check valve in response to movement of one of said levers away from said brake drum, a friction connection between said member and said one of said levers, and a stop means for limiting movement of said member in opposite directions incident to movement of said one of said levers towards and away from 55 60 65 70 75 80 85 90 95 said brake drum.
